UNITED STATES PATENT OFFICE.

THOMAS J. COONS, OF OSAGE CITY, KANSAS.

DESIGN FOR A TIP FOR CLOTHES-TONGS.

SPECIFICATION forming part of Design No. 23,562, dated August 14, 1894.

Application filed March 28, 1894. Serial No. 505,499. Term of patent 14 years.

To all whom it may concern:

Be it known that I, THOMAS J. COONS, a citizen of the United States, residing in Osage City, in the county of Osage and State of Kansas, have invented and produced a new and original Design for a Tip for Clothes-Tongs, of which the following is a specification.

Reference is to be had to the accompanying drawing, forming a part of this specification, in which the figure represents a perspective view of a tip embodying my new design.

The leading feature of my design consists in a tip having the ornamental configuration shown, to wit: having in general a V-shape, one member or leg *a*, of which extends be-

yond the other member *b*, and terminates in a rounded end edge *a'*, the member *b* being broadened at its end and presenting figures *c*, *c*, departing laterally from opposite sides and having rounded edges as shown and curving toward the member *a*, the member *a* further having along its sides a series of indentations *a''*.

I claim—

The design for a tip for clothes tongs, herein shown and described.

THOMAS J. COONS.
